SAW RETOOTHING MACHINE

Martin H. Wilbert, San Bruno, Calif.

Application August 23, 1947, Serial No. 770,294

5 Claims. (Cl. 76—29)

1

The object of my invention is to improve and simplify my Saw retoothing machine, Patent 2,300,717, by making new disposal of various parts as used therein, and using an entirely new and novel means for attaining vital manipulations so as to both simplify and contribute to the accuracy of the device.

A further object of my invention is to provide a device of the type described, which is simple to construct, compact in shape and efficient and accurate in the purpose intended.

Other objects and advantages will appear as the specification proceeds and the novel features of the invention will be particularly set forth in the appended claims.

My invention is illustrated in the accompanying drawings forming part of this application, in which:

Figure 1 is a top view of machine as drawn and described in Patent 2,300,717.

Figure 2 is a top view of traveling head and means of moving same.

Figure 3 is a front view of traveling head.

Figure 4 is a cross section through traveling head at D disclosing working parts in relief.

While I have shown only a simplified form of my invention, it should be understood that various changes or modifications may be made so as to use it as a hand operated device or to convert it to more complicated forms as necessary for air or hydraulic controls and appurtenances, within the scope of the appended claims and without departing from the spirit of the invention.

In carrying out my invention, I provide a frame indicated generally at A, Fig. 1, which consists of end castings 1 and 2 resting on a base 3 with cylindrical guide bars, either solid or tube, designated 4 and 5 extending between and supported by the end castings 1 and 2.

A sliding head B moves freely along the guide bars 4 and 5.

I provide an entirely new and novel means for stepwise advancing the head B along the guide bars 4 and 5 and designate the means for achieving this result as a cramp follower feed.

Within a head 11 which slides freely on guide bar 4 are two hardened flat washers with sharp edges 12, bored to a free fit on rod 4 and of a thickness which enables them to set side by side in the head and still leave space for a resilient material 30 or springs, between their outside faces and the inner faces of the head 11; the back of the inside of head is recessed to receive the rear edges of the washers and hold them to-

2

gether at the rear, while the front edges of the washers are free to move apart and may be spread so that they cramp on the guide bar 4 and have a lock grip on the bar; the spread of the washers is accomplished by a spreader pin which has a conical point 13 and this point will pry the washers apart and hold them apart; as long as this pin is holding the washers apart they are firmly locked to the bar 4 and as soon as pin is released a spring 14 which engages the fillister head of the pin, retracts the pin and frees the washers and the resilient material forces the washers into a parallel contact with each other, and they are now entirely free to slide on the bars.

A threaded sleeve 15 bored for a free sliding fit on bar 4 and fine threaded into head B along the line of bore for guide rods, makes it possible to open or close a space between the inner face 20 of this sleeve and the face of the cramp follower head 11; inserted pins 16 together with compression springs 17 in the sliding head boss which adjoins the opposite face of the cramp follower head 11 causes the follower head to fair up to the face of the threaded sleeve 15 and normally holds it there; with head 11 in this position, pressure may be applied to spreader pin 13 locking the head 11 to guide bar 4 by grip of the cramp washers 12, and the head 11 becomes a fixture, 25 to pry against, for moving the carrier one step along the guide rods; this forward movement of the sliding head continues until the rear boss is up against the follower head which now acts as a stop and the sliding head will have moved a distance equal to the space set by the threaded sleeve 15; when the pressure is removed from the spreader pin 13 the pins 16 thru action of springs 17 will advance the follower head into its normal 30 position against the face of the threaded sleeve or stop.

While there are many ways to apply pressure to the pin 13 for advancing the sliding head along the guide bars, such as air or hydraulic pistons or more simply by means of cams and levers I 45 will show a simple mechanical lever and cam means for accomplishing these results; on the pin end of head 11 and on opposite horizontal sides, two cams 18 are eccentrically mounted by means of studs which protrude from cams and 50 set into recesses in the head 11 see Figure 2; a cramping head 19 swings over the head end being mounted on the cams and swinging on the cam studs as pivots; square studs protrude from the opposite faces of the cams and directly opposite the pivot studs and these square studs en-

gage the fork of a lever 20 in such a way that swinging the lever rotates the cams and rotating the cams will draw the cramping head towards or move it away from the head 11; a hollow head set screw 21 is centrally located in the body of the cramping head 19 and in the cupped end of set screw a steel ball 22 rides and seats in a conical center in the fillister head of pin 13, thus allowing the cramping head 19 to pivot freely on the ball bearing as the cams rock the arms of the cramping head 19; this set screw 21 provides adjustment for setting proper throw in and out, to the spreader pin 13 so that when the lever 20 is swung directly straight out over the end of the cramping head 19 the pin 13 will give the proper degree of clamp to the washers 12 to lock the head 11 on the bar 4; then as the lever 20 is swung still further it will engage one end 15 of a lever pawl 26 which is pivotally mounted in a bracket formed on the head boss, into which the threaded sleeve is fitted; the other end of the pawl lever engages the cramp follower 11 and acts to pry the sliding head B along the guide bars 4 and 5.

As the lever 20 swings to extreme back position it releases the spread pin 13 from the cramp washers 12 and allows the head F to move freely on guide bar 4—the inserted pins 16 and springs 17 will now act to move the head 11 up against the adjusting sleeve 15 and the reaction of the pins and springs will tend to move the sliding head B in a counter movement; to prevent this reaction I employ a head lock washer 23 at rear end of the head boss; this cramp washer 23 is held cramped to the guide bar 4 by a tension spring 25 and the back of washer rides swingably on a pedestal fixed to the rear of boss; this head lock washer 23 positively locks head B against reverse motion and so when it becomes necessary to set sliding head B back to a starting position it becomes necessary to relieve the cramp washer 23; this is accomplished by a head release cam 24 mounted at rear end of head boss and which will engage the head lock washer 23 and hold it parallel to the face of the boss so that it will now slide freely on the guide bar 4.

Without further elaboration, this disclosure will so fully reveal the gist of the improvements, that others can by applying current knowledge, readily vary these improvements without omitting certain features, that from the standpoint of the prior art, fairly constitute essential characteristics of the specific and generic aspects of the improvements and therefore such variations are intended to be comprehended within the meaning and range of equivalency of the following claims.

I claim:

1. In a saw retoothing machine having a frame, using parallel guide bars and an adjustable tooth punch, a sliding head on which a punch is mounted, with a threaded sleeve fitted to the front boss of the sliding head and functioning to set the amount of stepwise advance, with a bracket attached to front boss which has a forked end, enabling a lever pawl to be pivoted and swung, for moving the sliding head along the guide bars; with a headlock washer for checking any reverse motion of head, with a cam release for the head lock washer and a cramp follower which acts to furnish the stepwise advance, acting both as a fulcrum and a reference point, from which any movement, imparted to the sliding head, may be controlled.

2. The device as set forth in claim 1, in which

a cramp follower feed is means for stepwise advancing the sliding head, and consists of a hollow head, which is bored crosswise for a free fit to the guide rod on which it travels or locks, and within this hollow head are two finished and hardened washers, which are also a free fit on the guide bar, at such times as they lie in full contact with each other and these washers are fitted neatly into a slot recess at rear of the follower head chamber so as to prevent any spread apart at this point, this recess serving further, to anchor the follower when the washers are locked to the guide bar, and a square end at the front of the hollow head, is drilled to fit a spreader pin shank and counterbored to the diameter of the fillister head of the pin and to a depth sufficient to contain a retracting spring, and a spreader pin, with a fillister head and a conical point, the head having a conical recess in the center to act as a seat for a steel ball bearing while the point of the pin is centrally located and directed to engage the contacting edges of the two washers so as to wedge them apart, and a resilient material or steel springs between the outside faces of the washers and the inside faces of the head chamber, providing an agent that holds the washers together flatwise except when pressure is applied to the spreader pin, to wedge the washers apart at their front edges, and cause them to clamp and lock to the guide bar, and in turn locking the follower head to the guide bar, and thus furnishing a fulcrum point for prying the sliding head forward, in stepwise advance, and also creating a reference point, from which the sliding head can be moved an exact distance.

3. The device as set forth in claim 1, in which a headlock washer supported at its rear edge by a pedestal bracket, attached to the rear of the sliding head, and pulled towards the head by a pair of balanced springs, which act at opposite sides and to the front of washer, so as to hold washer crammed to guide bar, locking the sliding head against any backward motion but freely following the forward advance of the head and which headlock washer may be rendered inactive, during such periods as it is desired to move the sliding head back to a starting point, by means of a knurled headed cam, set in the stepmount at rear of sliding head and in such a position that rotating the cam will lift the washer and hold it parallel to the face of head, in which position it will slide freely in both directions along the guide bars.

4. The device as set forth in claim 1, in which a sleeve, cut 32 threads to the inch on its outer diameter which makes it advance $\frac{1}{2}$ inch per turn, having a hexagon head for turning and calibrating, is threaded into the forward boss of the sliding head and varies the gap between its inner face and the adjoining face of the cramp follower feed when the sliding head is fared up to the rear face of the follower head and since this gap will represent the stepwise advance of the sliding head, it will be the measure of the size of tooth to be cut in saw.

5. In a saw retoothing machine having a carrier frame and an adjustable tooth punch, a sliding head freely mounted on guide bars in the carrier frame, and a cramp follower feed that is operated by means of cams and levers, in which a forked lever engages square studs to drive two cams, which are situated at the top and bottom of the square end of the follower head and embedded in the arms of a cramping head, and rotating on studs, projecting from the inner surfaces of the cams and fitting into recesses in the

square end of follower head to serve as bearings for the studs and a hollow head set screw centrally located in the body of the cramping head which contacts a ball bearing seated in the conical recess in the head of a spreader pin, with a filister head and a conical point and which serves to spread the cramp washers and thus lock the follower head against sliding so that as the cams are rotated by the forked lever, they will rock the cramping head on the ball bearing and pull it down against, or upward to release, the spreader pin, so that when the lever is moved to a position straight out over the cramping head, the maximum throw is given to the pin and the cramp washers are locked to the guide bar, thus locking the follower head, so that lever can be further oriented to contact the lever pawl which, using the follower head as a fulcrum, will pry the sliding head and stepwise advance it the width of the gap, set by the threaded sleeve, and when lever is returned to its starting position, then the follower head is free to move and the thrust of

the recessed pins and springs behind it, will fair the follower head up to the threaded sleeve thus closing the gap and also a headlock washer to prevent any reverse motion to the sliding head as it progresses along in its stepwise advance, a release cam to nullify the headlock washer when it is desirable to move the head in a backward direction, a threaded sleeve, calibrated for different widths of gaps conforming to different sized teeth in a saw, inserted springs and pins to set the follower head up to the threaded gage sleeve, when the cramp washers are unlocked and free movement restored to the follower head.
